(57) **CLAIM**

The ornamental design for a desk, as shown and described.

DESCRIPTION

FIG. 1 is a perspective view of a desk;
FIG. 2 is a front elevation view thereof;
FIG. 3 is a right side elevation view thereof;
FIG. 4 is a top plan view thereof;
FIG. 5 is a left side elevation view thereof;
FIG. 6 is a rear elevation view hereof;
FIG. 7 is a bottom plan view thereof;
FIG. 8 is a cross sectional view thereof, taken along line 8-8 of FIG. 2;
FIG. 9 is a cross sectional view thereof, taken along line 9-9 of FIG. 2;
FIG. 10 is a cross sectional view thereof, taken along line 10-10 of FIG. 3;
FIG. 11 is an enlarged view thereof, annotated portion 11 in FIG. 8; and,
FIG. 12 is an enlarged view thereof, annotated portion 12 in FIG. 9.

The one-dot broken lines in FIGS. 8 and 9 identify the areas that are illustrated in the enlarged views of FIGS. 11 and 12. The one-dot broken lines form no part of the claimed design.

1 Claim, 12 Drawing Sheets
